RECORD PERFORATING DEVICE

Ludwig M. Schmidt, Bad Vilbel, Kreis Friedberg, Germany, assignor to Sperry Rand Corporation, New York, N.Y., a corporation of Delaware

Filed Sept. 30, 1963, Ser. No. 312,409

Claims priority, application Germany Oct. 12, 1962

7 Claims. (Cl. 234—119)

This invention relates to a record perforating device and more particularly to an improved form of electrically operated high speed punch mechanism.

Conventional punching devices usually consist of a series of punch bars, one for each possible column or row position, known as a serial punching device, or one for every possible position on the card, known as a gang punch. Additionally, a heavy motor driven element known as the bail is provided for driving of the punch bars. Placed between the bail, which supplies the driving force and the punch bar which permits the actual perforation of the record, are a series of interposers employed to selectively transmit the bail power to the punch bars. The interposers in turn are connected to individual electromagnets which may be operated in accordance with some selection scheme. As a result of the large number of interposers which must be set and of the heavy weight of the bail which must be moved, certain time limits exist as to the maximum speed of operation of the device. Additionally, a timing problem exists in that the electromagnets to control the interposers must be selected during a time when the bail is not attempting to force the interposer and punch bar through the record. This puts a time limitation upon the possible actuating period for the electromagnets.

A positive mechanism is required to permit the returning of the punch bars to their initial positions from their record perforating position. This may involve in some manner the attachment by means of notches, springs, cams or other devices of a punch stripper possible requiring a further power source. The stripper operation creates a further timing problem in that it must be assured that all punch bars are in their proper position before the application of force by the bail member to attempt a punching operation. If such timing were not accurately controlled, punch bars or interposers might be broken or damaged. The motion of large numbers of pieces, for example the motion of the interposers and linkages additionally creates the problem of wear, even at punches which are relatively infrequently used as well as the production of noise.

The present invention overcomes many of the difficulties exhibited by prior art devices by employing a single punch operating lever which acts as interposer and punch stripper at the same time. The device further employs a drive means which incorporates both the punching driving means and the punch return driving means in a single unitary form so that accurate timing of the punching operation and the resetting or return operation is established. Further, the electromagnetic actuator is placed in close proximity to the punch operating lever so that it operates directly upon the punch operating lever thereby eliminating the wear, friction and noise accompanying the use of individual interposers, bails and connecting linkages.

In operation, the drive means is a cam disc which has upon it a punching cam and a return cam displaced from one another so as to provide a cam guide between them. When it is desired to operate the punch, the electromagnet for controlling an individual punch is actuated, forcing a cam following surface on one end of the punch operating lever to enter the cam guide. As the cam disc

2

is rotated by means of a motor and shaft, the punching cam will cause the punch operating lever to be pivoted in such a manner as to force the punch bar, connected at the opposite end of the punch operating lever, through the record. During this portion of the punching cycle the electromagnet may be deenergized to retract the armature from the surface of the punch operating lever. As the cam follower on the punch operating lever leaves the cam guide, the return cam operates upon the bottom

surface of the cam follower of the punch operating lever together with a biasing spring, which is placed between the punch operating lever and a support member, to restore the punch bar to its initial position. Due to the accurate placement of the punch and return cams on a single cam disc, synchronization between the punching and the return times is carefully insured. Additionally, the linkage in prior art devices required between the electromagnetic actuating device and the interposer is removed.

In the event that a punch operation is not to take place, in the device of the present invention, the cam follower of the punch operating lever will ride over top of the punching cam causing no relative movement of the punch operating lever or punch, thus decreasing the overall amount of friction and wear which normally are found in prior art devices. It is thus obvious that the punch operating lever will only be operated when a punching operation is necessary. A plurality of individual punch units, as described, may be stacked to permit the punching of as many positions as are desired along the punch line. The only requirement would be the placing of additional cams with the described punching and return cams along the length of the drive shaft at positions corresponding to the various punch positions along the punch line.

It is, therefore, an object of this invention to provide an improved form of electrically operated high speed punch mechanism.

It is still another object of this invention to provide an electrically operated high speed punching device which reduces the friction and wear normally accompanying prior art punching mechanisms.

It is yet another object of this invention to provide an electrically actuated high speed punching device which employs a unitary structure for operating the punch mechanism, and for providing a proper return or restoration of the punches.

It is still another object of this invention to provide an electrically actuated high speed punching device wherein the drive means is ineffective to operate the punch during non-selected or non-punching cycles of operation.

It is a further object of this invention to provide an electrically operated high speed punching mechanism wherein the interposer and interposer linkage as found in prior art devices are eliminated and wherein an electromagnetic actuating device is arranged to operate directly upon a punch operating lever to cause punching operations.

Further objects and features of the invention will be pointed out in the following descriptions and claims, and illustrated in the accompanying drawings which disclose, by way of example, the principles of the invention and the best mode which has been contemplated for carrying it out.

In the drawings:

FIGURE 1 illustrates a card punching device constructed in accordance with the basic concepts of the invention and illustrates the device in the non-select or non-punching mode.

FIGURE 2 illustrates a portion of the device of FIGURE 1 indicating the manner in which the electromag-

netic actuator causes the engagement of the cam follower of the punch operating lever with the cam guide.

FIGURE 3 illustrates the device of FIGURE 1 showing the punch in the position during a select or punching operation.

FIGURE 4 is a partial inverted view of the punch operating lever illustrating in greater detail the structure of the cam follower.

Similar elements are given similar reference characters in each of the respective figures.

Turning now to FIGURE 1, the device constructed in accordance with the basic concepts of the invention is illustrated. A punch operating lever 2 is pivotally mounted by means of a pivot pin 4 within the recess 6 of a support member 8 of the machine. The recess portion 6 is sufficient to allow the punch operating lever 2 to be moved in arcuate paths about the pivot 4 a sufficient distance to permit punching and retraction of the punch without interference. Punch operating lever 2 is an elongated lever with an ear 10 at a first end. A spring 12 is connected between the ear 10 and a spring holder 14. The spring holder 14 is attached by means of a fastener 16 to a spacer 18 which in turn is connected to the main body of the support member 8. The spring 12 is of sufficient strength to cause the punch operating lever 2 to be retained in the position shown in FIGURE 1 when not operated by any other external forces.

Intermediate the ear 10 and the pivot 4 along the punch operating lever 2 there is mounted a punch bar 20. Punch bar 20 has an aperture 22 at its lower edge adapted to engage the punch operating lever 2. The punch operating lever will be retained within the aperture 22 of the punch 20. The upper surface 3 of the punch operating lever 2 will operate upon the surface 24 of the aperture 22 during punch operations to cause the punch bar 20 to be operated upwardly and punch in a manner to be described below. During a removal or stripping operation, at which time the punch 20 is removed from the punch record, the bottom surface 5 of the punch operating lever 2 will contact the surface 26 of the aperture 22 and cause the punch to be moved downwardly. Punch bar 20 moves through an aperture 28 in a die block 30 thence into aperture 32 within a die plate 34. The die plate 34 and the die block 30 are placed sufficiently far apart to permit the insertion of a record 36 therebetween. The record is moved through this area between the die plate and the die block by means not shown.

At the opposite end of the punch operating lever, there is provided a lobe 38 and cam follower 40. The cam follower 40 is shown in phantom lines in FIGURE 1 in that it appears behind the surface of the punch operating lever 2. FIGURE 4 better illustrates the shape and arrangement of the cam follower 40 upon the punch operating lever 2. As can be seen in FIGURE 4, which is a partial view of a punch operating lever in an inverted position; that is, with the punch operating lever turned 180° in the plane perpendicular to the figure. Cam follower 40 is tear-drop in shape with a leading edge 42 being significantly smaller than the trailing edge 44. The leading edge 42 is shaped in such a manner as to be easily and smoothly insertable into a cam guide to be described below. The upper surface 46 between the leading edge 42 and the trailing edge 44 has a shape to permit a smooth application of force by the punching cam to be described below.

Turning again to FIGURE 1, a punch driving and return cam arrangement is shown. The punch drive and return arrangement is shown as a cam disc 48 driven by a shaft 50 which is in turn driven by a motor (not shown). The shaft 50 is mounted to the cam disc 48 by means of a key 52. Mounted upon the cam disc 48 is a return cam 54 and a punching cam 56. Cams 56 and 54 are so shaped and spaced from one another as to create a cam guide 58. During the non-select or non-punching cycle, the cam follower 40 on the punch operating lever 2 will

ride over a top surface 57 of the punching cam 56 without contact. When it is desired to cause punching, the electromagnetic actuator to be described below causes the cam follower 40 to engage the cam guide 58 causing the top surface 46 of the cam follower 40 to ride along the lower surface 59 of the punching cam 56. The cam follower 40 will proceed through the cam guide 58, and upon leaving, return cam 54 will then contact the lower surface 47 of the cam follower 40 causing the punch operating lever 2 to be moved as will be described below.

Electromagnetic actuator 60 is provided for controlling the position of the punch operating lever 2 with respect to the cam disc 48. The actuator 60 consists of a set of coils 62 connected to a selection circuit 64. The selection circuit is employed to control the current applied to the coils 62, in response to external signals which are applied to the terminals 66. The coils 62 are wound upon cores which have inclined pole faces 74. The inclination of the pole faces 74 is such that a maximum gap occurs between the faces 74 at the upper edges of the faces and decreases to a minimum gap at the bottom edge of the faces 74. Placed within the coils 62 is a two section armature structure 68 having a frusto-conical upper section 69, whose side edges are adapted to engage the pole faces 74. The second or lower section 70 of the armature 68 is cylindrical in shape with a rounded bottom edge. The armature structure 68 is normally biased by means of a spring 72 to be maintained out of contact with the pole faces 74 of the coils 62. When a signal is applied to the terminal 66 a current will then be provided by the selection circuit 64 to the coil 62 causing the armature section 69 to be drawn against and in contact with the pole faces 74. Movement of the armature in the proper plane is controlled by means of guide pins 76 extending from the electromagnet frame 61 to the armature 68. As a result of this downward motion of the armature 68, the spring 72 is placed in compression and the armature portion 70 is made to engage the lobe 38 of the punch operating lever 2. As a result of this operation, the punch operating lever 2 will be moved downwardly about pivot 4 causing the cam follower 40 to engage the cam guide 58.

The manner of operation of the device of FIGURE 1 will now be described with reference to FIGURES 1, 2 and 3. When a punch operation is desired, a signal is applied to the terminals 66 of the selection circuit 64. This signal may originate at a keyboard, a punch card reader, a computer or any other suitable input source. The selection circuit 64 will provide a current to the coils 62 of the electromagnetic device 60. This will cause the armature 68 to be drawn from the position as shown in FIGURE 1 against the effects of the spring 72, and causing the armature portions 70 to engage the lobe 38 of the punch operating lever 2. The movement of punch operating lever 2 as a result of the contact between armature portion 70 and lobe 38 of the punch operating lever 2, is not sufficient to cause a punching operation. The aperture 22 of the punch 20 is made sufficiently large so that the rotation of the punch operating lever 2 about pivot pin 4, does not place the upper surface 3 of the punch operating lever 2 in contact with the surface 24 of the aperture 22. The relative timing between the application of a current by the selection circuit 64 and the rotation of the cam disc 48 is such that the current may be applied any time from the trailing edge of the return cam 54 leaving the proximity of cam follower 40 to just prior to the leading edge of the punch cam 56 arriving at the proximity of the cam follower 40. The timing is not critical in that the cam disc is ineffective during this time to control punching operations.

The position of the cam follower 40 of the punch operating lever 2 as it enters the cam guide 58 is shown in FIGURE 2. The armature 68 is shown, in the fully engaged position causing the spring 72 into maximum compression. The portion 70 has operated against the

lobe 38 and the leading edge 42 of the cam follower 40 has entered the cam guide 58. As the cam disc 43 continues to rotate the upper surface 46 of the cam follower will follow the lower surface 59 of the punch cam 56, causing the punch operating lever 2 to be pivoted in a clockwise direction about pivot 4. As a result, the surface 3 of the punch operating lever 2 engages the surface 24 of the aperture 22 of the punch 20 whereby the punch 20 is moved upwardly as the lever 2 is rotated. The relative curvatures of the cam follower 40 and the punch cam 56 are so chosen that sufficient rotation of the punch operating lever 2 is achieved to permit the punch 20 to be moved through the aperture 28 in the die block 30 through the record 36 into the aperture 32 in a die plate 34. It should be noted that all drive power for punching is provided by the cam disc 43 motor unit and that the armature 70 merely serves to control the position of cam follower 40.

Once the cam follower 40 has entered the cam guide 58, the current provided by the selection circuit 64 may be turned off. The control of the punch operating lever 2 from this point forth will be by means of the cam disc 43. Thus, in FIGURE 3 there is illustrated the arrangement of the components of FIGURE 1 during the punching cycle after the selection circuit 64 stops providing current to the electromagnetic means 60. The punch bar continues its upward movement but the armature 68 is returned to its initial position by means of spring 72 along the guide pins 76.

Further, FIGURE 3 illustrates the relationship of the punching cam 56 and the cam follower 40 at the position of maximum travel of the punch bar 20. It should be noted from FIGURE 3 that the spring 12 has been stretched as the punch operating lever 2 has been rotated. It should further be noted that for further rotation of the cam disc 43 the lower surface 47 of the cam follower 40 will begin to engage surface of the return cam 54. The cam follower 40 will continue in the cam guide 58 for a short portion of the following rotation of the cam disc 43. However, as the cam follower 40 leaves the cam guide 58, the cam follower 40 will be acted upon only by means of the return cam 54. The action of the return cam 54 on the lower surface 47 of the cam follower 40, concurrently with the attempt of the spring 12 to compress to its normal position as shown in FIGURE 1 causes the punch operating lever 2 to be rotated in a counter-clockwise direction to return to its static position as shown in FIGURE 1. The maximum return force will be exerted at the time that the highest point of return cam 54 is engaging a lower surface 47 of the cam follower 40. During the further rotation of the cam disc 43 no further forces are exerted on the punch operating lever 2 by means of the cam disc 43. The punch 20 has now been returned to its rest position as shown in FIGURE 1, and is ready for further operation.

The cycle just described with reference to a single punching operation will be repeated for every punching operation required. As was described above, at times when no punching operation or the non-select cycle is called for the cam follower 40 merely rides over the top surface 57 of the punching cam 56 without relative motion of the punch operating lever 2. As a result of this mode of operation, frictional forces which are normally created at bearings are greatly reduced. Further, it is obvious by means of the direct application of a force by the armature portion 70 of the electromagnetic means 60 to the punch operating lever 2 the need for an interposer and for linkages between such electromagnetic means and an interposer for setting it are eliminated. By selection of proper speeds of rotation and dimensions of the various cams and cam followers, a smooth, relatively noiseless interaction between the cam follower and cams can be achieved, thus eliminating the noise normally associated with punching devices. Further, by means of the unitary structure placing the punching cam 56 and the return cam

54 upon a single cam disc 43 a positive return means for the punch is provided without the necessity of additional equipment and the usual synchronization problems.

Only a single punch unit has been shown and described. 5 It should be obvious to those skilled in the art that the device may be expanded to provide for the punching of as many columnar positions as are desired. That is, for a serial arrangement 12 or 80 positions may be provided depending upon the direction of feed of the card. Additionally, if it is desired to provide this as a gang punch 10 960 of these units would be provided to permit punching of all positions at the same time. In order that, for example, a 12 punch assembly might be constructed the support member 8 would be provided with 12 recesses 15 such as 6. Punch operating levers 2 would be provided in each of the recesses. A single shaft 50 would be provided with properly spaced cam discs 43 and punching and return cams 56 and 54 respectively, spaced along the shaft to cooperate with the individual cam followers 40 20 of the punch operating levers 2. A separate set of punches and actuators 60 would be required for each punch unit. A single guide block 30 and guide plate 34 would be required with a plurality of apertures 28 and 32 therein, respectively.

25 While there has been shown and described and pointed out the fundamental novel features of the invention as applied to the preferred embodiment, it will be understood that various omissions and substitutions and changes of the form and details of the device illustrated and its operation may be made by those skilled in the art, without departing from the spirit of the invention.

The embodiments of the invention in which an exclusive property or privilege is claimed are defined as follows:

35 1. In a record perforating device, a punching assembly comprising: a punch operating lever, said lever arranged to be moved in arcuate paths; a punch bar coupled to a first end of said punch operating lever and movable by said lever to a position to permit perforation of a record; 40 biasing means connected to said punch operating lever to place said lever in a non-perforating position; drive means to selectively move said punch operating lever between said non-perforating position and said record perforating position, and means selectively operable to cause said punch operating lever to engage said drive means; said drive means comprising a driven cam disc having a return cam and a separate punch cam, said punch cam being so placed upon said cam disc as to hold said punch operating lever in engagement with said drive means during said record perforation, whereby said punch cam controls the position of said punch operating lever after said selectively operable means ceases to cause said punch operating lever to engage said drive means.

2. In a record perforating device, a punching assembly 55 comprising: a punch operating lever, said lever arranged to be moved in arcuate paths; a punch bar coupled to a first end of said punch operating lever and movable by said lever to a position to permit perforation of a record; biasing means connected to said punch operating lever to place said lever in a non-perforating position; drive means to selectively move said punch operating lever between said non-perforating position and said record perforating position, said drive means comprising a driven cam disc having a return cam and a punching cam, said cams being placed upon said cam disc to form a cam guide; and means selectively operable to cause said punch operating lever to engage said cam guide; said cam guide controlling said punch operating lever during said record perforation and after said selectively operable means ceases to cause said punch operating lever to engage said cam guide.

3. In a record perforating device, a punching assembly 60 comprising: a punch operating lever, said lever arranged to be moved in arcuate paths; said lever further having a cam follower surface mounted at a first end of said

lever; a punch bar coupled to said second end of said lever and adapted to be moved by said lever to a position to permit perforation of a record; biasing means connected to said lever to place said lever in a non-perforating position; drive means adapted to selectively move said lever between said non-perforating position and said record perforating position, said drive means comprising a driven cam disc having a return cam and a punching cam, said cams being placed upon said cam disc to form a cam guide; and actuator means selectively operable to cause said lever cam follower surface to enter said cam guide and cause said lever to be moved in a first direction and move said punch bar to said perforating position, said lever further moving in a second direction to move said punch bar to said non-perforating position upon said cam follower surface leaving said cam guide, the movement of said lever in said second direction being caused by said return cam and by said biasing means.

4. A device as claimed in claim 3, wherein said actuator means is an electrically operable magnet.

5. A device as claimed in claim 3, wherein said actuator means is a selectively operable electromagnet, which when operated causes its armature to engage said punch operating lever placing said cam follower surface in said cam guide, said electromagnet operation being terminated shortly after the entry of said cam follower surface into said cam guide.

6. In a record perforating device, a punching assembly comprising: a punch operating lever, said lever arranged to be moved in arcuate paths; a punch bar coupled to a first end of said punch operating lever, said punch bar normally remaining in a non-perforating position and movable by said lever to a position to permit perforation of a record; drive means to selectively move said punch operating lever between said non-perforating position and said record perforating position, and means se-

lectively operable to cause said punch operating lever to engage said drive means; said drive means comprising a driven cam disc having a return cam and a separate punch cam, said punch cam being so placed upon said cam disc as to hold said punch operating lever in engagement with said drive means during said record perforation whereby said punch cam controls the position of said punch operating lever after said selectively operable means ceases to cause said punch operating lever to engage said drive means.

7. In a record perforating device, a punching assembly comprising: a punch operating lever, said lever arranged to be moved in arcuate paths; a punch bar coupled to a first end of said punch operating lever, said punch bar normally remaining in a non-perforating position and movable by said lever to a position to permit perforation of a record; drive means to selectively move said punch operating lever between said non-perforating position and said record perforating position; and means selectively operable to cause said punch operating lever to engage said drive means; said drive means comprising a driven cam disc having a return cam and a holding means, said holding means being so placed upon said cam disc as to hold said punch operating lever in engagement with said drive means during said record perforation, whereby said holding means controls the position of said punch operating lever after said selectively operable means ceases to cause said punch operating lever to engage said drive means.
